(57) **CLAIM**

The ornamental design for an ergonomic wine glass stem, as shown and described.

DESCRIPTION

FIG. 1 is a top front perspective view of an ergonomic wine glass stem, showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a top front perspective view thereof, shown in use. The dash-dash broken lines shown in the drawings depict portions of the article that form no part of the claimed design. The dash-dash broken lines shown in FIG. 8 depicting a hand are environmental subject matter that forms no part of the claimed design. The dot-dash broken lines shown in FIGS. 2-5 define the bounds of the claimed design and form no part thereof.

1 Claim, 5 Drawing Sheets
